UNITED STATES PATENT OFFICE.

SAMUEL GEORGE TATE, OF CHICAGO, ILLINOIS, ASSIGNOR TO UNION SPECIAL MACHINE COMPANY, OF CHICAGO, ILLINOIS, A CORPORATION OF ILLINOIS.

DEVICE FOR POSITIONING LOOPERS OF SEWING-MACHINES FOR THREADING.

1,316,400.

Specification of Letters Patent. Patented Sept. 16, 1919.

Application filed December 18, 1917. Serial No. 207,677.

To all whom it may concern:

Be it known that I, SAMUEL GEORGE TATE, a citizen of the United States, residing at Chicago, in the county of Cook, State of Illinois, have invented certain new and useful Improvements in Devices for Positioning Loopers of Sewing-Machines for Threading, of which the following is a description, reference being had to the accompanying drawing and to the figures of reference marked thereon.

The invention relates to new and useful improvements in sewing machines and more particularly to the devices for moving the looper from its normal operating position to a position at one side of the throat plate to facilitate threading of the looper.

Prior to my invention devices have been provided for locking the main operating shaft and for shifting the looper carrier to position the looper for threading. Devices have also been provided for locking the operating shaft and for releasing the latch which holds the looper carrier in place for normal operation for permitting the looper carrier to be engaged by hand and moved laterally thereby to threading position. An object of the present invention is to provide means for locking the shaft against movement, for releasing the latch which holds the looper carrier in operative position on its support and for shifting the looper carrier laterally to threading position, all of which may be accomplished by a single manually operated member.

A further object of the invention is to provide a sewing machine having an opening at one side of the throat plate, a plurality of loopers arranged side by side and parallel with the line of feed and means accessible at the front of the work support for locking the driving shaft of the machine against movement and for moving the loopers laterally beneath the opening for threading.

A still further object of the invention is to provide means for locking the manually operated member from movement when the same is out of engagement with the shaft so as to prevent any accidental movement of the manually operated member.

A still further object of the invention is to provide devices which are so constructed that the looper carrier is moved from normal to threading position by the manually oper-

ated member and said carrier is returned to normal operating position by a spring.

These and other objects will in part be obvious and will in part be hereinafter more fully described.

In the drawings, which show by way of illustration one embodiment of the invention,

Figure 1 is a front view of a sewing machine having my improvements applied thereto;

Fig. 2 is an enlarged view of a portion of the machine, showing the work support and throat plate in section and the parts beneath the machine in front elevation;

Fig. 3 is a view partly in section and partly in plan showing the parts beneath the work support with the loopers in normal operating position and the manually operated member locked in idle position;

Fig. 4 is a view similar to Fig. 3 but showing the manually operated lever released and swung sufficiently to lock the main shaft and to release the latch which holds the looper carrier;

Fig. 5 is a view similar to Fig. 3 but showing the manually operated lever swung so as to position the loopers underneath the opening in the work support where they may be easily threaded;

Fig. 6 is a plan view of a portion of the work support showing the slide thrown back to uncover the opening through which the loopers are threaded and showing a portion of the work support broken away and the mechanism for oscillating the loopers in plan;

Fig. 7 is a vertical sectional view through the work support and the parts beneath the same, substantially on the line of feed, also showing a portion of the overhanging arm, the presser foot and the needle carried thereby;

Fig. 8 is a vertical sectional view substantially on the line of feed, showing the looper, the looper carrier, the looper support, the feed bar, the feed dog carried thereby, the needle and the presser foot, the looper being in normal operating position;

Fig. 9 is a view similar to Fig. 8 but showing the latch released so that the looper carrier may be moved endwise to threading position; and

Fig. 10 is a sectional view through the locking sleeve on the main shaft.

My invention is particularly adapted for a sewing machine having a thread carrying looper coöperating with the needle for forming double locked chain stitches. The thread carrying looper is mounted on a carrier which is, in turn, mounted on a carrier support. The carrier is connected to the support so that it is capable of endwise movement on the support but is always oscillated with the support. A latch operates to hold the carrier with the looper in normal position to coöperate with the needle.

My improvement consists in the means for releasing the latch, locking the machine against movement and for sliding the looper carrier to position where the looper may be readily reached for threading. In the present embodiment of the invention the devices for accomplishing this function include a hand operated lever which is normally out of engagement with a locking collar on the main shaft and which when swung engages said locking collar to hold the shaft from turning. This hand operated lever is also connected to a sliding collar which has a limited lost motion on the looper carrier so that the first movement of the lever which brings about the locking of the shaft also releases the latch and a further movement of the lever moves the carrier to bring the looper to threading position. A spring normally holds the looper carrier in operative position and returns the looper carrier to operative position when the hand lever is swung back again to idle or non-locking position. A locking dog is used for securing the hand lever in idle position so as to prevent the same from being accidentally engaged with the main shaft.

Referring more in detail to the drawings, I have shown my invention as applied to a machine having a work support 1, a bed plate 2, carrying an overhanging arm 3 in which a needle bar 4 reciprocates. The needle bar is reciprocated by a lever 5 which is oscillated by an eccentric strap 6, coöperating with an eccentric on the main shaft 7. The needle bar, as herein shown, is provided with two needles 8 and 9. The material is held on the work support by a presser foot 10 which is of the usual construction. The material is fed across the work support by a feed dog 11 carried by a feed bar 12 which is also of the usual construction and is operated so as to impart the desired movements to the feed dog.

Coöoperating with the needle 8 beneath the work support is a thread carrying looper 13 and coöperating with the needle 9 is a thread carrying looper 14. It will be understood that a single needle and looper may be used or more than two needles and coöperating loopers may be used. The number of needles and coöperating loopers has nothing to do

with my invention except that when the number of loopers are multiplied and arranged in the line of feed the difficulties in threading the loopers are increased. My invention is directed particularly to this type of machine and means for shifting the loopers to a position where they may be easily reached for threading.

The loopers 13 and 14 are mounted on a looper carrier 15. This looper carrier is in turn mounted on a looper carrier support 16. The support 16 is in the form of a shaft mounted in suitable bearings carried by the bed plate 2. This looper carrier support is oscillated through a suitable link and a crank at the forward end of the main shaft 7, as clearly shown in Fig. 6 of the drawings, wherein the crank is indicated at 17 and the link, which is moved thereby, at 18. The looper carrier support 16 is also moved endwise so that the looper may be moved laterally for its needle avoiding movement. This is accomplished by means of a sleeve 19 which is secured to the inner end of the looper support 16. A rod 20 is attached to said sleeve and this rod is connected by a link 21 to a rock lever 22. The rock lever 22 is in turn connected to an eccentric strap 23 coöperating with an eccentric on the main shaft 7. These devices for oscillating the looper carrier support and for moving the same endwise are well known in the art and form no part of the present invention.

The looper carrier 15 consists of two spaced collars 15^a and 15^b which are connected by bars 24 and 25. The bar 25 projects laterally from the collars and is formed with a slot 26. The loopers 13 and 14 are attached to this slotted bar by suitable screws 27. The collars 15^a and 15^b are free on the looper support 16. Clamped to the looper support 16 is another collar 28 which has a laterally projecting forked portion 29 which straddles the bar 24 (see Fig. 7). The bar 24 is capable of sliding endwise in the forked extension 29 but this collar 28 with its forked extension through its connection with the bar 24 prevents the looper carrier from oscillating on its support so that said looper carrier will be oscillated in timing with the oscillations of the support 16 but said carrier is free to move endwise on said looper support 16. When the looper carrier 15 is in position so that the loopers will coöperate with the needles, the collar 15^b is brought into contact with the collar 28. The carrier is locked in this position by a latch 30. This latch 30 is pivoted between the forked members of the extension 29. Said latch is carried by a pivot screw 31 and a spring 32 surrounding this pivot screw serves to force the latch so as to hold its locking lip 33 in engagement with a shoulder 34 on the collar 15^b. When the parts are in this position the carrier is

locked both as to sidewise movement and oscillating movement to the carrier support 16 and will oscillate with the support and move laterally as the support moves endwise.

5 The work support of the machine is indicated at 1 in Fig. 6 of the drawings. Said work support carries a throat plate 35 having feed slots 36 through which the feed dog 11 operates. Said throat plate also has needle openings 37 through which the needles operate. The loopers move in a vertical plane containing the line of feed and are during their entire movement beneath the throat plate so that it is very difficult to thread the 15 same when in their operative position. The work support is provided with an opening 38 at one side of the throat plate 35 and this opening is closed by a cover plate 39. When the latch 30 is released the looper carrier 20 may be moved endwise on the looper carrier support 16 so as to bring the loopers into the opening 38, as clearly shown in Fig. 6 of the drawings. When so positioned they are readily accessible to the operator for threading.

25 The means for moving the looper carrier and for releasing the latch includes a hand lever 40 which is mounted on a fulcrum post 41 so that it may be swung about the same in a horizontal plane. This hand lever performs the functions of locking the main shaft against movement as well as releasing the latch and shifting the looper carrier. The locking of the main shaft is accomplished by means of an extension 42 on the hand lever 30 engaging a notch 43 in a collar 44 fixed to the main shaft 7. When the hand lever 40 is in the position shown in Fig. 3, the extension 42 is free from the notch so that the main shaft may rotate. When this hand lever is shifted even to a slight extent, as for example, to the position shown in Fig. 4, the extension will enter the slot and prevent the shaft 7 from rotating until the extension is withdrawn from the slot. Of course, the 45 machine will have to be stopped or the shaft 7 turned to bring the slot 43 into position to be engaged by the extension 42 before the hand lever can be swung. In other words, the extension 42 lies close to the outer surface of the collar 44 and as this extension extends at an angle to a plane at right angles to the main shaft and passing through the center of the fulcrum post 41, any movement of the hand lever to the right, as 50 viewed in Fig. 3, will be prevented by the extension 42 engaging the outer face of the collar 44. When, however, the slot is in register with this extension then the hand lever may be moved. The looper carrier 15 has a 55 sleeve 45 extending therefrom and this sleeve surrounds the looper carrier support 16. The sleeve is formed with an integral collar 46 at the outer end. Mounted to slide on this sleeve is a ring 47. The ring 47 is pivoted between the ends of a yoke 48 formed

as a part of a link 49 which in turn is adjustably pivoted at 50 to the hand lever 40. The ring 47 is considerably less in width than the distance between the collar 46 and the collar 15^b of the looper carrier so that this 70 ring has a lost motion or idle movement on the sleeve 45. The ring has an extending finger 51 which is adapted to engage the latch 30. The latch 30 is formed with a tapered projection 52 which is adapted to be engaged 75 by this finger 51. When the lever 40 is turned from the position shown in Fig. 3, to the position shown in Fig. 4, the ring 47 slides on the sleeve 45 to a point substantially in contact with the collar 46 and during this 80 movement on the ring the finger 51 will engage the tapered projection 52, and move the latch 30 back so as to release the looper carrier. A further movement of the hand lever 40 to the position shown in Fig. 5, will cause 85 the ring 47 to engage the collar 46 and move the looper carrier 15 on the looper carrier support 16, bringing the loopers to a position beneath the opening 38 in the work support. 90

A spring 53 encircles the looper carrier 16 and is partly housed in the bearing 54 for the looper carrier 16. This spring bears against the end of the sleeve 45 and normally tends to move the carrier to the left 95 as viewed in Figs. 3 to 5 inclusive. When the hand lever 40 is moved to the left from the position shown in Fig. 5, the spring will force the carrier to the left, holding the collar 46 against the ring 47 until the parts 100 reach the position shown in Fig. 4. At this point the carrier has been brought back to its normal operative position and any further movement of the hand lever to the position shown in Fig. 3 releases the latch 105 so as to lock the carrier to the carrier support 16 and this brings the ring 47 back away from the collar 46.

As a means for preventing accidental movement of the hand lever 40 and also for holding the carrier with the loopers in threading position, I have provided a locking dog 55 which is adapted to engage either the notch 56 or the notch 57 in the fulcrum post 41 on which the lever 40 turns. When 110 this locking dog 55 which is pressed forward by a spring 58, engages the notch 56, it will lock the lever against movement and at this time the looper carrier is held with the loopers in position for threading. When 115 this locking dog engages the notch 57, as shown in Fig. 3 then the lever 40 is locked and the looper carrier is positioned for the normal operation of the loopers and at this time the hand lever is free from engagement 120 with the notch in the collar 44. The dog 55 is actuated by a hand piece 59 which lies alongside of the lever 40.

It is believed that the operation of my device will be apparent from the above de- 130

scription. The machine is brought to a stop or turn so that the groove 43 is in register with the extension 42 on the hand lever 40. At this time the loopers are retracted, are 5 out of the needle loops and free from striking the needle, if moved sidewise. A movement of the hand lever locks the machine so that it cannot be turned and at the same time releases the latch which holds the 10 looper carrier to the looper carrier support. A further movement of the hand lever causes the looper carrier to slide endwise on the looper carrier support, bringing the loopers beneath the opening in the work support and to position for threading. After 15 the loopers have been threaded the operator moves the hand lever in the opposite direction which permits the looper carrier to be returned to normal operative position 20 for the loopers. This releases the latch and the main shaft so that the machine may be started.

It will be apparent that the locking of the machine, the releasing of the looper carrier 25 and the movement of the looper carrier laterally to bring the loopers to threading position, is all brought about through a single lever moving in one direction.

It will be noted from the above that I 30 have also provided a machine having an opening at one side of the throat plate and a plurality of loopers located side by side and movable in lines parallel with the line of feed and also means accessible at the 35 front of the work support whereby the main shaft may be locked, the looper carrier released from its support and the loopers moved beneath the opening for threading, and this can only be accomplished when the 40 loopers are withdrawn from the needle loops and positioned so that they may be readily moved laterally.

It is obvious that minor changes in the details of construction and in the arrangement of parts may be made without departing from the spirit of the invention as set forth in the appended claims.

Having thus described my invention, what I claim as new and desire to secure by Letters Patent, is:—

1. A sewing machine including in combination a needle, a thread carrying looper coöperating with said needle, a looper carrier on which the looper is mounted, a looper 55 carrier support, means for operating the looper carrier support for imparting movements to the looper, retaining means for securing the carrier to its support, a manually operated member, devices operated by said 60 member for locking the carrier support against movement, for releasing the retaining means and for moving the looper carrier on its support to place the looper in position for threading.

nation, a needle, a thread carrying looper coöperating with said needle, a looper carrier on which the looper is mounted, a looper carrier support, means for operating the looper carrier support for imparting 70 movements to the looper, retaining means for securing the carrier to its support, a manually operated member, devices operated by said member for locking the carrier support against movement, for releasing the 75 retaining means, and for moving the looper carrier on its support to place the looper in position for threading, and means for locking said manually operated member with the looper in normal position for coöperating 80 with the needle.

3. A sewing machine including in combination, a needle, a thread carrying looper coöperating with said needle, a looper carrier on which the looper is mounted, a looper carrier support, means for operating the looper carrier support for imparting 85 movements to the looper, retaining means for securing the carrier to its support, a manually operated member, devices operated by said member for locking the carrier support against movement, for releasing the retaining means and for moving the looper carrier on its support to place the looper in position for threading, yielding 90 means for returning the looper to the normal operating position.

4. A sewing machine including in combination, a needle, a thread carrying looper coöperating with said needle, a looper carrier on which the looper is mounted, a looper carrier support, means for operating the looper carrier support for imparting movements to the looper, retaining means for securing the carrier to its support, a manually operated member, devices operated by 100 said member for locking the carrier support against movement, for releasing the retaining means and for moving the looper carrier on its support to place the looper in position for threading, yielding 105 means for returning the looper to the normal operating position, and means for locking said manually operated member with the looper in position for threading.

5. A sewing machine including in combination, a needle, a thread carrying looper coöperating with said needle, a looper carrier on which the looper is mounted, a looper carrier support, means for operating the 110 looper carrier support for imparting movements to the looper, a latch for securing the carrier to its support, a manually operated lever having means for locking the looper carrier support against movement and devices operated by said lever for releasing the latch and for moving the looper carrier on its support to place the looper in position 115 for threading.

bination, a needle, a thread carrying looper coöperating with said needle, a looper carrier on which the looper is mounted, a looper carrier support, means for operating 5 the looper carrier support for imparting movements to the looper, a latch for securing the carrier to its support, a manually operated lever having means for locking the looper carrier support against move- 10 ment and devices operated by said lever for releasing the latch and for moving the looper carrier on its support to place the looper in position for threading, and a spring for returning the looper carrier to 15 normal operative position.

7. A sewing machine including in combination, a needle, a thread carrying looper coöperating with said needle, a looper carrier on which the looper is mounted, a looper carrier support, means for operating 20 the looper carrier support for imparting movements to the looper, a latch for securing the carrier to its support, a manually operated lever having means for locking the looper carrier support against movement, and devices operated by said lever for releasing the latch and for moving the looper carrier on its support to place the looper in position for threading, a spring for 25 returning the looper carrier to normal operative position and means for locking the operating lever with the looper in position for threading.

8. A sewing machine including in combination, a needle, a thread carrying looper coöperating with said needle, a looper carrier on which the looper is mounted, a looper carrier support, means for operating the looper carrier support for imparting 30 movements to the looper, a latch for securing the carrier to its support, a manually operated lever having means for locking the looper carrier support against movement, and devices operated by said lever 40 for releasing the latch and for moving the looper carrier on its support to place the looper in position for threading, a spring for returning the looper carrier to normal operative position and means for locking 45 the operating lever with the looper in position for threading, and for locking the lever from movement when the looper is in normal operative position.

9. A sewing machine including in combination, a main shaft, a needle, a thread carrying looper coöperating with said needle, a looper carrier on which the looper is mounted, a looper carrier support, means for oscillating said carrier support and for 50 moving the same endwise for imparting the proper movements to the looper, means for causing the carrier to oscillate with the carrier support, said means permitting the carrier to move endwise on the support, a 55 latch for holding the carrier from endwise

movement on the support when the looper is in position for coöperation with the needle, a hand lever, said hand lever having means for engaging and locking the main shaft against movement, devices operated by said 70 hand lever for releasing said latch and for moving said carrier endwise on the looper carrier support to threading position.

10. A sewing machine including in combination, a main shaft, a needle, a thread carrying looper coöperating with said needle, a looper carrier on which the looper is mounted, a looper carrier support, means for oscillating said carrier support and for moving the same endwise for imparting the 75 proper movements to the looper, means for causing the carrier to oscillate with the carrier support, and means permitting the carrier to move endwise on the support, a latch for holding the carrier from endwise 80 movement on the support when the looper is in position for coöperation with the needle, a hand lever for releasing the latch and moving the looper carrier laterally to position the looper for threading, a collar 85 on the main shaft, said collar having a groove therein, said hand lever having an extension adapted to engage said groove and lock the machine against movement while the looper carrier is moved away from 90 operative position, said collar being so positioned relative to the extension as to prevent movement of the hand lever until said extension is in register with said groove.

11. A sewing machine including in combination, a main shaft, a needle, a thread carrying looper coöperating with said needle, a looper carrier on which the looper is mounted, a looper carrier support, means for oscillating said carrier support and for 100 moving the same endwise for imparting the proper movements to the looper, means for causing the carrier to oscillate with the carrier support, said means permitting the carrier to move endwise on the support, a latch for holding the carrier from endwise 105 movement on the support when the looper is in position for coöperation with the needle, a hand lever, a sleeve carried by the looper carrier, a collar on said sleeve, a ring, a finger carried by said ring and adapted to engage said latch, said ring having a free 110 movement on said sleeve so as to release the latch before moving the carrier endwise, and a link for connecting the hand lever 115 to said ring.

12. A sewing machine including in combination, a main shaft, a needle, a thread carrying looper coöperating with said needle, a looper carrier on which the looper is mounted, a looper carrier support, means for oscillating said carrier support and for moving the same endwise for imparting the proper movements to the looper, means for causing 125 the carrier to oscillate with the carrier sup- 130

port, said means permitting the carrier to move endwise on the support, a latch for holding the carrier from endwise movement on the support when the looper is in position for coöperation with the needle, a hand lever, a sleeve carried by the looper carrier, a collar on said sleeve, a ring, a finger carried by said ring and adapted to engage said latch, said ring having a free movement on said sleeve so as to release the latch before moving the carrier endwise, a link for connecting the hand lever to said ring, a spring for engaging the carrier and for returning the same to normal operative position.

13. A sewing machine including in combination, a main shaft, a needle, a thread carrying looper coöperating with said needle, a looper carrier on which the looper is mounted, a looper carrier support, means for oscillating said carrier support and for moving the same endwise for imparting the proper movements to the looper, means for causing the carrier to oscillate with the carrier support, said means permitting the carrier to move endwise on the support, a latch for holding the carrier from endwise movement on the support when the looper is in position for coöperation with the needle, a hand lever, a sleeve carried by the looper carrier, a collar on said sleeve, a ring, a finger carried by said ring and adapted to engage said latch, said ring having a free movement on said sleeve so as to release the latch before moving the carrier endwise, a link for connecting the hand lever to said ring, said hand lever having means for locking the machine against movement when the looper is moved from operative position.

14. A sewing machine including in combination, a main shaft, a needle, a thread carrying looper coöperating with said needle, a looper carrier on which the looper is mounted, a looper carrier support, means for oscillating said carrier support and for moving the same endwise for imparting the proper movements to the looper, means for causing the carrier to oscillate with the carrier support, said means permitting the carrier to move endwise on the support, a latch for holding the carrier from endwise movement on the support when the looper is in position for coöperation with the needle, a

hand lever, a sleeve carried by the looper carrier, a collar on said sleeve, a ring, a finger carried by said ring and adapted to engage said latch, said ring having a free movement on said sleeve so as to release the latch before moving the carrier endwise, a link for connecting the hand lever to said ring, a spring for engaging the carrier and for returning the same to normal operative position, said hand lever having means for locking the machine against movement when the looper is moved away from operative position.

15. A sewing machine including in combination, a driving shaft, a feeding mechanism, a work support having a throat plate, an opening at one side of the throat plate, a plurality of needles, a looper coöperating with each needle, a looper carrier for said loopers, said loopers being placed side by side and moving respectively in lines parallel with the line of feed, and means including a lever beneath the work support and accessible at the front of the machine for locking the driving shaft against movement, for releasing the looper carrier from its support and for moving the looper carrier laterally to position the loopers beneath the opening in the work support for threading.

16. A sewing machine including in combination, a driving shaft, a feeding mechanism, a work support having a throat plate and an opening at one side of the throat plate, a plurality of needles, a looper coöperating with each needle, a looper carrier for said loopers, said loopers being placed side by side and movable respectively in lines parallel with the line of feed and means beneath the work support and accessible at the front of the machine for locking the driving shaft, for releasing the looper carrier from its support and for moving the looper carrier to position the loopers underneath the opening in the work support, said means including a lever moving in a single plane.

In testimony whereof I affix my signature in the presence of two witnesses.

SAMUEL GEORGE TATE.
